UNITED STATES PATENT OFFICE.

JOHN J. SCULLY, OF BRIDGEPORT, CONNECTICUT, ASSIGNOR TO COLUMBIA GRAPHOPHONE MANUFACTURING COMPANY, OF BRIDGEPORT, CONNECTICUT, A CORPORATION OF DELAWARE.

WINDING MECHANISM FOR SPRING-MOTORS.

1,351,405.

Specification of Letters Patent. Patented Aug. 31, 1920.

Application filed July 29, 1918. Serial No. 247,282.

To all whom it may concern:

Be it known that I, JOHN J. SCULLY, a citizen of the United States of America, and a resident of Bridgeport, Connecticut, have 5 invented a new and useful Improvement in Winding Mechanism for Spring-Motors, which invention is fully set forth in the following specification.

This invention relates to means for facilitating the operative engagement of a winding crank with the winding arbor of a talking-machine spring motor which motor is surrounded by a casing the wall of which is relatively remote from the arbor, being 10 sometimes spaced as far as ten or twelve inches therefrom. As the point of engagement of the crank with the arbor is entirely concealed, it is frequently difficult to bring the mating ends of the crank and arbor into 15 operative engagement. Usually the arbor-connecting end of the crank is blindly gyrated within the casing on the casing wall escutcheon as a fulcrum until, more or less accidentally, connection is made with the 20 arbor. The futile attempts at making connection with the arbor cause annoyance. This is to be regretted because the whole 25 purpose of the talking-machine is to give pleasure.

30 It is an object of this invention to provide means whereby the crank may be promptly brought into operative engagement with the arbor, thus avoiding the annoying delays and difficulties indicated above.

35 The invention will be described in connection with the accompanying drawings in which,

Figure 1 is an inverted plan view of a talking machine provided with an embodiment of the present invention and showing the winding arbor and crank in separated relationship and the guide member partially broken away for the sake of clearness; and

40 Fig. 2 is a detailed view, on an enlarged scale, of one form of the guide member.

45 Referring in detail to said drawings, 1 designates a spring motor of any suitable construction, the same being shown as a driving element of a talking machine of any 50 preferred construction. 2 designates a surrounding casing provided with an escutcheon 3 through which the winding crank 4 is inserted into engagement with the winding arbor of said motor. In the form

shown, said arbor takes the form of a tubular shaft 5 carrying a pinion 6 and rotatably mounted in any suitable way as in the bracket 7. Said arbor 5 is shown as provided with interior screw-threads for coaction with exterior threads 8 on the end of 60 crank 4. To the arbor is suitably connected a funnel-shaped guide member 9 which is shown as provided with a flared outer end 10 and a cylindrical inner end 11 whereby the latter may be received in telescopic relation to the arbor 5 and suitably maintained in position as by a collar 12 and set-screw 13.

In operation, the guide member 9, owing to its flared outer end 10 in concentric relation to the winding arbor, engages the inner 70 end of the crank 4 as the same is inserted through the escutcheon 3 and guides the same into operative engagement with the arbor. Thereby the crank may be quickly 75 brought into operative engagement with the arbor and, in the form shown, rotated to engage the threads 8 with the threads 7 for connecting the mating sections of said crank and arbor. It will therefore be seen that, even though the distance between the wall of 80 the casing 2 and the end of the winding arbor be relatively great, the winding crank may be brought into operative relation to the arbor promptly, and without experimentation and annoying delays incident to the 85 engagement of the crank with the arbor in prior devices.

While the preferred mechanical expression of the invention has been described with considerable particularity it is obvious 90 that various changes may be made in the details of construction without departing from this invention and it is, therefore, to be understood that this invention is not to be limited to the specific construction. 95

What is claimed is:—

1. In combination, a spring motor having a winding arbor, a sleeve telescoped over said arbor and secured thereto, a wall spaced from said arbor and having an opening 100 therein, a winding shaft projecting through said opening, and a funnel-shaped member carried by said sleeve and facing said opening.
2. In combination, a spring motor having a winding arbor, a sleeve telescoped over said arbor, a collar telescoped over said sleeve, means carried by the collar for secur-

ing the sleeve in fixed relation to said arbor, a wall spaced from said arbor and having an opening therein, a winding shaft projecting through said opening, and a funnel-shaped member carried by said sleeve and facing said opening.

3. In combination, a spring motor having a winding arbor, a wall spaced therefrom and having an opening therein, a winding

shaft projecting therethrough, and a guiding means for said shaft comprising a sleeve telescoped over and secured to said arbor, and a funnel-shaped extension coaxial with said sleeve and facing said opening.

In testimony whereof I have signed this 15 specification.

JOHN J. SCULLY.
